UNITED STATES PATENT OFFICE

2,115,606

PROCESS FOR HYDROCARBON OIL
CONVERSION

Joseph G. Alther, Chicago, Ill., assignor to Universal Oil Products Company, Chicago, Ill., a corporation of Delaware

Original application April 17, 1929, Serial No. 355,704. Divided and this application June 27, 1936, Serial No. 87,689

14 Claims. (Cl. 196—60)

This is a division of my co-pending application Serial No. 355,704, filed April 17, 1929, now Patent No. 2,091,261.

This invention relates to improvements in process for hydrocarbon oil conversion, and refers more particularly to improvements designed for the efficient cracking of hydrocarbon oils to convert and produce therefrom products having higher commercial value.

10 The utility of the invention as well as many objects and advantages thereof will be brought out in the following description.

The principal object of the invention is to subject hydrocarbon oil to such conditions of temperature and pressure as to produce maximum yields of lighter gravity products suitable for use as motor fuel with a minimum coke and gas loss.

Another object is to provide for lowering the reflux ratio by making it possible to convert a greater proportion of the higher boiling point hydrocarbons per pass through the unit. This is of particular importance in effecting the capacity and thermal efficiency of the process.

Another purpose of the invention resides in the employment of means to increase the decomposition of both the vapors and liquid from the pressure expansion drum under controlled conditions designed to accomplish the best results. This feature not only has an effect in increasing the yields of lighter hydrocarbons obtained from the operation but also in improving their quality, especially for use as a motor fuel, in that they will consist more largely of higher antiknock compounds.

35 Briefly, the process of the present invention is as follows:

The charging stock plus reflux will be pumped through a conventional furnace having a large heating surface from which the heated oil may be transferred to a drum. This drum may be unheated but lagged against excessive radiation losses. Expansion takes place in the drum from which vapors may be withdrawn separately, passing preferably through a vapor heating coil to provide further conversion and into a zone of lower pressure into which residual oil from the expansion drum may be directed.

From this point on the usual operation takes place, i. e., all the vapors from the flashing still are directed to a dephlegmator where the sufficiently converted fractions are separated from the heavier ends (reflux) by the incoming cold raw oil or other cooling medium, said reflux being returned to the cracking coil for retreatment.

55 In order to more clearly understand the inven-

tion, I have shown the accompanying drawing, which is a diagrammatic view, but not to scale, of an apparatus suitable for carrying out the invention.

Referring to the drawing and to the operation 5 of the invention, the oil to be treated is directed through line 1 and branch 2, having valve 3 into a heating coil 4, located in a furnace 5.

In heating coil 4 the oil is heated to a temperature within the cracking range under a suitable 10 pressure. The amount of oil passed through the coil per unit time, and the size of the apparatus are so correlated that under the temperatures and pressures used the degree of cracking obtained in the heating coil is preferably short of that degree of reaction at which formation of coke and sludge-like matter occurs, or exceeds a predetermined desired degree.

Chamber 10 may take any desired form and size 15 in relation to the capacity of the apparatus. It may be unheated and insulated against loss of heat by radiation and may be maintained at a temperature not substantially higher than the temperature of the oil introduced thereto from heating coil 4 through line 6 and valve 7.

On the other hand, particularly for the heavier 20 charging stocks and depending upon the limitations imposed upon the amount of coke and sludge to be formed or contained in the products, it may be desirable to maintain the materials in chamber 10 at a temperature lower than that reached at the discharge of heating coil 4 to decrease the rate at which the reaction proceeds in chamber 10. To this end the oil may be cooled 25 in a manner hereinafter described.

The pressures on the expansion chamber may be substantially that of the coil outlet or lower, but in the preferable operation this pressure should be as high as possible in order to increase the capacity of the unit and raise the thermal 30 efficiency of the process.

The vapors pass out of chamber 10 through line 19 and, as a feature of the invention, I may subject all or part of the vapors removed from chamber 10 to additional heating at elevated temperatures to effect a controlled degree of so-called vapor-phase cracking whereby I am enabled to produce lighter valuable distillates having the characteristics of motor fuels or gasoline, possessing high anti-knock properties due to the presence of controlled proportions of aromatic and unsaturated hydrocarbons formed by said vapor cracking.

For this purpose a vapor coil 22 may be positioned in furnace 5 and located therein in such 35

a manner that the combustion gases pass over coil 22 before passing over coil 4. In this manner and because the combustion gases passing over coil 22 are at a higher temperature than when 5 they pass over coil 4, a greater degree of radiant heat may be utilized in coil 22 than in coil 4. Coil 22 may be connected to vapor line 19 through branches 23 and 24, respectively, controlled by valves 25 and 26. By proper regulation of valves 10 20, 25, and 26, any desired amount of vapors separated in chamber 10 may be passed through the vapor heating coil 22. The vaporous products from line 19, including the heated products supplied thereto from coil 22 pass through line 15 100 into chamber 54 at any desired point in this zone by regulation of valves 57, preferably entering the lower portion of this zone and commingling therein with the liquid products supplied, as will be later described, from chamber 10 20 to chamber 54, whereby to supply additional heat to said liquid products and assist their further vaporization.

The heavier liquid products are withdrawn from chamber 10, preferably from the bottom 25 thereof, through line 51 having valve 52 and are directed to flash chamber 54 to be subjected therein to flash distillation to any desired degree. Chamber 54 is provided with a bottom-draw-off 61, having valve 62, whereby liquid or 30 semi-solid products may be removed therefrom. Solid matters formed in the operation of the process and deposited in chamber 54 may be removed therefrom through top and bottom manholes in the usual manner.

35 Raw oil to be treated in the process may be drawn from suitable storage tanks (not shown) through line 43 and pump 44. From line 43 and by suitable control of the valves shown, all or a portion of the raw oil to be treated in the process 40 may be diverted through line 45, having valve 46, then to line 47 which connects with the main feed line 1, whereby all or a portion of the charging stock may be fed directly to the heating tubes.

Vapors separated by flash distillation in chamber 54 may be removed therefrom through line 48 having valve 67 to fractionating column 69, wherein they are subjected to controlled condensation by introducing into dephlegmator 69 50 suitable cooling medium through line 70 having valve 71; or raw oil to be charged to the process may be diverted from line 43 through line 72, having valve 73 and introduced to column 69.

Vapors uncondensed in column 69 may be removed therefrom through upper draw-off line 55 74, having valve 75, and passed to condenser 76, thence to receiver 77, having usual gas release valve 78 and distillate release valve 79. The fractions of the vapors condensed in column 69 may be discharged from the bottom thereof through 60 line 80, in which may be interposed pump 81, from which they are directed through line 84, having valve 85, connected with feed line 47, whereby said fractions may be returned directly to heating coil 4.

65 It may be desirable to control the degree of reaction respectively taking place in heating coil 4, chamber 10 and vapor coil 22, by controlling the temperature, characteristics and quality of materials passing respectively through these 70 zones. For instance, it may be desirable to introduce into the oil transferred from heating coil 4 to chamber 10, liquid products or condensates from other parts of the process. It may also be desirable to do the same thing for the vapors 75 withdrawn from chamber 10. In addition it may

be desirable to cool the vapors immediately after they are subjected to vapor-phase cracking in coil 22. Suitable lines and valves (not shown) may be provided whereby material passing through line 47 may be diverted and injected into line 24 through which the vapors leave coil 22. Line 90 controlled by valve 90' is also provided for introducing regulated quantities of the materials passing through line 47 into line 19 and provision is also made for diverting regulated 10 quantities of oil from line 1 through line 87 and valve 87' into line 6.

A portion of the non-condensable gas from receiver 77 may be returned to vapor line 19 leaving reaction chamber 10 by means of valve 15 92 in line 93. This gas will pass through coil 22 together with the vapors from the reaction chamber or be by-passed through valve 20, depending upon the operation desired. In any event the uncondensed gas and vapors may be introduced into chamber 54 at any desired point in this zone and, in the event the liquid level in chamber 54 is above the point of introduction, the hot gas and vapors will act as a partial pressure agent to facilitate vaporization in this zone. 20 By controlling the point of entry by means of valves 57, the vapors may enter flash chamber 54 either above or below the liquid level maintained therein. If full advantage of partial pressure effect of these vapors is to be taken, they 30 should enter at the lowest point in chamber 54 in order to increase vaporization and facilitate reduction of the percentage of unvaporized oil.

The valves and pumps shown permit the operator to maintain suitable pressures on the various 35 parts of the apparatus. The flash chamber 54 and its connected parts such as dephlegmator 69, condenser 76 and receiver 77 are preferably maintained at a pressure substantially lower than the pressure maintained in chamber 10. Any suitable 40 pressure may be maintained in vapor cracking coil 22 in relation to the pressure maintained in chamber 10. Heating coil 4 in chamber 10 may be maintained at substantially the same pressure or the pressure maintained in chamber 10 45 may be lower than that maintained in the heating coil although still substantially above atmospheric pressure.

As an illustration of the temperatures which 50 may be maintained in an operation carried out in accordance with the invention, the oil may be heated in heating coil 4 to a temperature of, say 920° F. to 960° F., said oil entering chamber 10 at a temperature near but relatively lower than said temperature. In chamber 10 the oil may be 55 maintained at a temperature of, say 850 to 900° F. The vapors leaving chamber 10 and recycled gases from receiver 77 may be heated in vapor coil 22 to a temperature of approximately 975 to 1100° F. In this illustration a pressure of approximately 450 pounds may be maintained on heating coil 4 and chamber 10. The pressure may be reduced on flash chamber 54 down to approximately 25 pounds. The vapors leaving 60 chamber 10 may be passed through vapor coil 22 under a pressure of approximately 100 pounds, more or less.

It is to be understood that the preferred method of operation is of the low level type, where- 70 in a minimum quantity of residual oil is maintained in the chamber 10. That is, residual oil is withdrawn from chamber 10 before it has had sufficient time to form more than 5 per cent of sludge or coke-like constituents.

I claim as my invention:

1. In a process wherein hydrocarbon oil charging stock is heated to a temperature sufficient to effect substantial vaporization thereof, its resulting vaporous and liquid components separated and the vapors supplied to a separate cracking zone wherein they are subjected to temperature and pressure conditions regulated to effect the production therefrom of high yields of good antiknock gasoline, the improvement which comprises commingling relatively hot conversion products from said cracking zone with said liquid components, whereby to effect appreciable further vaporization of the latter, removing the remaining unvaporized residue from the system, subjecting the vaporous products including those resulting from further vaporization of said liquid components to fractionation for the formation of reflux condensate, subjecting fractionated vapors of the desired end-boiling point to condensation, separating the resulting distillate and uncondensed gases, recovering the distillate, and returning a portion of the uncondensed gases to said cracking zone and therein heating the same to an oil cracking temperature together with said vaporous components supplied thereto.
2. In a process wherein hydrocarbon oil charging stock is heated to a temperature sufficient to effect substantial vaporization thereof, its resulting vaporous and liquid components separated and the vapors supplied to a separate cracking zone wherein they are subjected to temperature and pressure conditions regulated to effect the production therefrom of high yields of good antiknock gasoline, the improvement which comprises commingling the relatively hot conversion products from said cracking zone with said liquid components, whereby to effect appreciable further vaporization of the latter, removing the remaining unvaporized residue from the system, subjecting the vaporous products, including those resulting from the further vaporization of said liquid components, to fractionation for the formation of reflux condensate, returning reflux condensate formed by said fractionation to further treatment within the system, subjecting fractionated vapors of the desired end-boiling point to condensation, separating the resulting distillate and uncondensed gases, recovering the distillate and returning a portion of the uncondensed gases to said cracking zone and therein heating the same to an oil cracking temperature together with said vaporous components supplied thereto.
3. In a process wherein hydrocarbon oil charging stock is heated to a temperature sufficient to effect substantial vaporization thereof, its resulting vaporous and liquid components separated and the vapors supplied to a separate cracking zone wherein they are subjected to temperature and pressure conditions regulated to effect the production therefrom of high yields of good antiknock gasoline, the improvement which comprises commingling relatively hot conversion products from said cracking zone with said liquid components, whereby to effect appreciable further vaporization of the latter, removing the remaining unvaporized residue from the system, subjecting the vaporous products, including those resulting from the further vaporization of said liquid components, to fractionation for the formation of reflux condensate, commingling reflux condensate formed by said fractionation with the charging stock undergoing treatment in the first mentioned heating stage of the system, subjecting fractionated vapors of the desired end-boiling point to condensation, separating the resulting distillate and uncondensed gases, recovering the distillate, reheating a portion of the uncondensed gases to a high oil-cracking temperature and commingling the same directly and without substantial cooling thereof with said liquid components from the first-named heating stage.
4. In a process wherein hydrocarbon oil charging stock is heated to a temperature sufficient to effect substantial vaporization thereof, its resulting vaporous and liquid components separated and the vapors supplied to a separate cracking zone wherein they are subjected to temperature and pressure conditions regulated to effect the production therefrom of high yields of good antiknock gasoline, the improvement which comprises commingling relatively hot conversion products from said cracking zone with said liquid components, whereby to effect appreciable further vaporization of the latter, removing the remaining unvaporized residue from the system, subjecting the vaporous products, including those resulting from the further vaporization of said liquid components, to fractionation for the formation of reflux condensate, subjecting fractionated vapors of the desired end-boiling point to condensation, separating the resulting distillate and uncondensed gases, recovering the distillate, reheating a portion of the uncondensed gases to a high oil-cracking temperature and commingling the same directly and without substantial cooling thereof with said liquid components from the first-named heating stage.
5. In a process wherein hydrocarbon oil charging stock is heated to a temperature sufficient to effect substantial vaporization thereof, its resulting vaporous and liquid components separated and the vapors supplied to a separate cracking zone wherein they are subjected to temperature and pressure conditions regulated to effect the production therefrom of high yields of good antiknock gasoline, the improvement which comprises commingling relatively hot conversion products from said cracking zone with said liquid components whereby to effect appreciable further vaporization of the latter, removing the remaining unvaporized residue from the system, subjecting the vaporous products, including those resulting from the further vaporization of said liquid components, to fractionation for the formation of reflux condensate, commingling reflux condensate formed by said fractionation with the charging stock undergoing treatment in the first mentioned heating stage of the system, subjecting fractionated vapors of the desired end-boiling point to condensation, separating the resulting distillate and uncondensed gases, recovering the distillate, reheating a portion of the uncondensed gases to a high oil-cracking temperature and commingling the same directly and without substantial cooling thereof with said liquid components from the first-named heating stage.
6. In a process wherein hydrocarbon oil charging stock is subjected to cracking temperature at substantial superatmospheric pressure, the resulting vaporous and liquid conversion products separated and the vapors subjected to appreciable additional conversion at increased temperature in a separate cracking zone, the improvement which comprises commingling the additionally cracked vapors, while still at a higher temperature than said liquid products, with the latter in a separate zone, whereby appreciable fur-

ther vaporization of the liquid products and appreciable cooling of the additionally cracked vapors is accomplished, subjecting the vaporous products from said separate zone to fractionation for the formation of reflux condensate, returning reflux condensate formed by said fractionation to the first mentioned cracking step, subjecting fractionated vapors of the desired end-boiling point to condensation, separating the 5 resulting distillate and uncondensed gases, recovering the distillate and returning a portion of the uncondensed gases to the second mentioned cracking step and heating the same therein to said increased temperature together with the 10 first-mentioned vapors.

7. In a process wherein hydrocarbon oil charging stock is subjected to cracking temperature at substantial superatmospheric pressure, the resulting vaporous and liquid conversion products separated and the vapors subjected to appreciable additional conversion at increased temperature in a separate cracking zone, the improvement which comprises commingling the additionally cracked vapors, while still at a 15 higher temperature than said liquid products, with the latter in a separate vaporizing zone, whereby appreciable further vaporization of the liquid products and appreciable cooling of the additionally cracked vapors is accomplished, 20 subjecting the vaporous products from said separate vaporizing zone to fractionation for the formation of reflux condensate, returning reflux condensate formed by said fractionation to the first mentioned cracking step, subjecting fractionated vapors of the desired end-boiling point to condensation, separating the resulting distillate and uncondensed gases, recovering the 25 distillate, reheating a portion of the uncondensed gases to a high oil-cracking temperature and introducing the same directly and without substantial cooling thereof into said separate vaporizing zone.

8. In a process wherein hydrocarbon oil charging stock is subjected to cracking temperature at substantial superatmospheric pressure, the resulting vaporous and liquid conversion products separated and the vapors subjected to appreciable additional conversion at increased temperature in a separate cracking zone, the improvement which comprises commingling the additionally cracked vapors, while still at a higher 45 temperature than said liquid products, with the latter in a separate zone, whereby appreciable further vaporization of the liquid products and appreciable cooling of the additionally cracked vapors is accomplished, subjecting the vaporous products from said separate zone to fractionation for the formation of reflux condensate, returning reflux condensate formed by said fractionation to the first mentioned cracking step, subjecting fractionated vapors of the desired end-boiling point to condensation, separating the resulting distillate and uncondensed gases, recovering the 50 distillate and returning a portion of the uncondensed gases to further treatment in the same cracking step to which said vaporous products are supplied and heating the same therein to said increased temperature together with the first-mentioned vapors.

9. In a cracking process wherein hydrocarbon oil charging stock is subjected to cracking conditions in a heating coil, the resulting heated products introduced into a separating chamber wherein their vaporous and liquid components 55 separate and from which they are separately re-

moved, the vapors subjected to vapor-phase cracking conditions in a separate heating coil and supplied therefrom to a separate chamber wherein they are afforded additional conversion time, the improvement which comprises contacting relatively hot vapors resulting from said vapor-phase cracking with liquid conversion products withdrawn from said separating chamber, whereby to effect appreciable further vaporization of the latter, recovering the remaining 1 unvaporized residue, subjecting the vaporous products, including those evolved from the liquid products by said further vaporization, to fractionation, supplying reflux condensate formed by said fractionation to the first mentioned 15 cracking operation, subjecting fractionated vapors of the desired end-boiling point to condensation, recovering and separating the resulting distillate and uncondensed gases, reheating a portion of the latter to a relatively high temperature and introducing the reheated gases directly and without substantial cooling thereof into said second mentioned chamber.

10. The improvement as defined in claim 9 further characterized in that said portion of 25 the uncondensed gases is reheated in said separate coil in admixture with the first-named vapors.

11. A conversion process which comprises passing hydrocarbon oil through a heating coil and 30 heating the same therein sufficiently to vaporize a substantial portion thereof, separating resultant vapors from unvaporized oil in an enlarged zone, removing the unvaporized oil and introducing the same into a second enlarged zone, removing 35 vapors from the first-named enlarged zone and heating the same to vapor phase cracking temperature in a second heating coil, subsequently introducing the vapor phase cracked vapors into contact with the unvaporized oil in said second 40 enlarged zone, removing admixed vapors and gases from the second enlarged zone and subjecting the same to condensation to separate vapors from gases, heating a portion of the separated uncondensed gases to a high oil- 45 cracking temperature and subsequently introducing the same directly and without substantial cooling thereof into contact with the unvaporized oil in said second enlarged zone.

12. The process as defined in claim 11 further 50 characterized in that said portion of the gases is heated in said second coil in admixture with the vapors being heated therein to vapor phase cracking temperature.

13. In a hydrocarbon oil conversion process 55 wherein there is formed a mixture of vapors and gases which is fractionated and then subjected to final condensation and the incondensable gases separated from the final condensate, the method which comprises heating hydrocarbon oil to distillation temperature in a heating coil and separating the same into vapors and unvaporized oil in a separating chamber, introducing the unvaporized oil into a second chamber maintained under lower pressure than the first-named chamber, simultaneously heating vapors from the first-named chamber and a portion of said incondensable gases to a high oil-cracking temperature, introducing the thus heated vapors and gases into contact with the unvaporized oil in 60 said second chamber, and supplying admixed vapors and gases from the second chamber to said fractionating step.

14. In a hydrocarbon oil conversion process 75 wherein there is formed a mixture of vapors and

gases which is fractionated and then subjected to final condensation and the incondensable gases separated from the final condensate, the method which comprises heating hydrocarbon oil to distillation temperature in a heating coil and separating the same into vapors and unvaporized oil in a separating chamber, introducing the unvaporized oil into the upper portion of a second chamber maintained under lower pressure than

0 the first-named chamber, simultaneously heat-

ing vapors from the first-named chamber and a portion of said incondensable gases to a high oil-cracking temperature, introducing the thus heated vapors and gases into the lower portion of the second chamber to flow in countercurrent contact with said unvaporized oil, and supplying admixed vapors and gases from the second chamber to said fractionating step.

JOSEPH G. ALTHER. 10
